UNITED STATES PATENT OFFICE.

LEONIDAS C. SCHMIDT, OF HOUSTON, TEXAS.

SAFETY ATTACHMENT FOR LOCKS.

Application filed May 2, 1927. Serial No. 188,227.

This invention relates to new and useful improvements in a safety attachment for locks.

One object of the invention is to provide a safety attachment for locks of safes, vaults and the like which is designed for use in connection with the usual combination lock and whereby the lock bolts may be secured against release in certain cases of attempted burglary of the safe or vault, or of mutilation of, or unauthorized interference with the combination lock, the invention relating particularly to the provision of a pivotally mounted tumbler associated with the lock bar and normally inactive in combination with means adapted to be released in case of interference with the combination lock and which is adapted to engage with and lock the tumbler in active position to prevent the operation of said lock bar and the bolts carried thereby.

Another object of the invention is to provide a safety attachment of the character described including a pivotally mounted tumbler which will remain idle, or inactive during the normal operation of the combination lock and will not interfere with said operation but when, upon unauthorized interference with the combination mechanism of the safe or vault lock will operate to lock the bolts thereof against release.

With the above and other objects in view the invention has particular relation to certain novel features of construction, operation and arrangement of parts, an example of which is given in this specification and illustrated in the accompanying drawings, wherein:—

Figure 1 shows a fragmentary inside elevational view of a safe door showing the combination lock and the safety attachment installed and showing the adjacent part of the safe in section.

Figure 2 shows a cross sectional view thereof taken on the line 2—2 of Figure 1, and

Figure 3 shows a vertical sectional view thereof taken on the line 3—3 of Figure 1.

Referring now more particularly to the drawings, wherein like numerals of reference

designate similar parts in each of the figures, the numeral 1 designates the safe proper, having the usual door 2 hinged thereto in the usual way. Installed on the inside of the door is the lock mechanism presently to be described. The numerals 3, 3, designate the bolts or plungers which are secured to the bolt bar 4 and which are disposed to project into aligned holes 5, 5, in the adjacent facing of the door opening to lock the safe door 60 in closed position. There is a dead bolt 6, having a bearing in the door and whose outer end carries a suitable knob 7 by means of which the dead bolt may be turned, and whose inner end has a fixed arm 8 whose free end works in the bearing notch 9 of the shift bar 10, attached to the bar 4. The numeral 11 designates the usual combination lock controlling mechanism located on the inside of the door and which may be manipulated by means of the hand knob 12 on the outside, in combination with a graduated dial 13. The controlling mechanism 11 locks the shift bar 10, and consequently the bolts, 3, 3, against release in one position, but when the dial has been turned to give its movements a certain order of succession the bar 10 is released to permit the lock to be unlocked through the bolt 6. The shift bar 10 is operatively connected with the controlling mechanism in the usual and conventional manner.

The combination lock above described is of conventional construction and the safety attachment embodying the invention will now be described.

The numerals 14, 14, designate transverse bearings attached to the inside of the door 2 and in these bearings there is a rotatable shaft 15, one end of which has a projecting stud 16 whose free end normally rests in a bearing 17 in the free end of the release bar 18. The other end of this release bar is attached to the controlling mechanism 11, preferably by means of set screws 19, which are fitted therethrough and screwed into said controlling mechanism. The controlling mechanism 11 embodies a conventional latch 20, and attached to the inside of the door 2 and overlying said latch is a release arm 20' 100

one end of which is free and extends underneath the free end of the release bar 18. The other end of the shaft 15 has the safety bolts 21, 21, fixed thereto, one of which is adjacent the inside of one bearing 14 and a set screw 22 is screwed into said shaft 15 adjacent the inner side of the other bearing 14 thus preventing the lengthwise movement of said shaft. There is a tumbler pivoted to 10 the innerside of the door and designated generally by the numeral 23. This tumbler has the upstanding arm 24 aligned between the safety bolts 21 and said tumbler also has a lateral finger 25 and opposite this finger is 15 enlarged forming a balance weight 26 which normally holds the finger 25 against the bolt bar 4 but permits it to operate in the usual manner, said tumbler operating idly when said bolt bar is so operated. When the shaft 20 15 is held in inactive position by the stud 16 the safety bolts 21 extend outwardly at substantially right angles to the door but when said stud is released by the bar 18 the safety bolts fall by gravity and interlock with the 25 arm 24 so as to lock the tumbler finger 25 against the bolt bar 4 and to thus prevent the withdrawal of the bolts 3.

When a safe is burglarized it is usually accomplished by forcibly displacing the controlling mechanism 11 or the latch 20 thereof, so as to release the locking mechanism to permit the operation of the dead bolt 6. When the safety attachment herein described is used upon displacement of, or interference 35 with, the controlling mechanism 11, or the latch 20 thereof the release bar 18 will be forced inwardly and released from the stud 16 and thereupon the safety bolts 21 will drop down by gravity into interlocking relation with the arm 24 and the tumbler finger will thereby be locked against the inside of 40 the bolt bar 4 and the locking mechanism will thereby be held in locked position.

What I claim is:—

45 1. In a lock the combination with a lock bolt, and a controlling mechanism adapted to secure said bolt in locked position or to release the same to permit operation thereof, of a pivotally mounted tumbler, a safety bolt 50 adapted to interlock with said tumbler when in active position, a rotatable shaft supporting the safety bolt, means adapted to hold said safety bolt in inactive position, said means including a holder supported by the 55 controlling mechanism.

60 2. In a lock the combination with a lock bolt and a controlling mechanism adapted to secure said bolt in locked position, or to release the same to permit operation thereof, said mechanism being subject to displacement by violence, of a movably mounted tumbler associated with said bolt and operable idly when said bolt is operated, a safety bolt 65 adapted, when in active position, to engage with said tumbler, to lock the tumbler against

movement and to thereby lock said lock bolt against operation, means adapted to hold said safety bolt in inactive position, said means being carried by said controlling mechanism and having a releasable connection with said safety bolt.

3. In a lock, the combination with a lock bolt, and a controlling mechanism, adapted to secure said bolt in locked position, or to release the same to permit operation thereof, of a pivotally mounted tumbler associated with said bolt and adapted to be locked against movement to prevent the operation of said bolt, a safety device adapted, when in active position, to engage with, and lock, the tumbler against movement, means for holding said safety device in inactive position, out of engagement with the tumbler, said means being releasable.

4. In a lock the combination with a lock bolt and a controlling mechanism adapted to secure said bolt in locked position, or to release the same to permit operation thereof, of a yieldably mounted member associated with said bolt and adapted to be locked against movement to prevent the operation of said bolt, a safety device adapted, when in active position to engage with and lock the yieldable member against movement and to thereby prevent operation of said lock bolt, means for holding said safety device in inactive position out of engagement with said yieldable member, said means being carried by said controlling mechanism and being releasable to permit said safety device to move into active position to lock said yieldable member.

5. In a lock, the combination with a lock bolt, and a controlling mechanism adapted to secure said bolt in locked position or to release the same to permit operation thereof, of a pivotally mounted tumbler associated with said bolt and adapted to be locked against movement to prevent the operation of said bolt, a safety device adapted, when in active position to engage with and lock the tumbler against movement, said safety device including a rotatable shaft and means carried thereby adapted to interlock with the tumbler, means carried by said controlling mechanism and releasably engaging said shaft to hold the safety device in inactive position.

6. In a lock the combination with a lock bolt bar, and a lock bolt attached thereto and controlling mechanism subject to displacement by violence and adapted to secure said bolt in locked position, or to release the same to permit operation thereof, of a yieldable member associated with said bar and adapted to be locked thereagainst to prevent the operation of said bar and bolt carried thereby, said yieldable member, when released, operating idly, during the operation of said bar, a safety device adapted, when

in active position, to engage with and lock the yieldable member against movement, means associated with said controlling mechanism and releasably connected to said safety device and adapted to hold said safety device in inactive position out of engagement with said yieldable member, and adapted to

be released, upon displacement, of said controlling mechanism, to permit said safety device to move by gravity into locking relation with said yieldable member. 10

In testimony whereof I have signed my name.

LEONIDAS C. SCHMIDT.
